D11-4. OR D11.599 EX

NO. Des. 11.599

JAN. 13, 1880

UNITED STATES PATENT OFFICE.

JOHN H. SHOEMAKER, OF NEWARK, NEW JERSEY.

DESIGN FOR A BRACELET.

SPECIFICATION forming part of Design No. 11,599, dated January 13, 1880.

Application filed October 11, 1879. Term of patent 3½ years.

To all whom it may concern:

Be it known that I, JOHN H. SHOEMAKER, of the city of Newark, in the county of Essex and State of New Jersey, have invented a new and original Design for Bracelets, of which the following is a full, clear, and exact description, reference being had to the accompanying photographic illustration, making part of this specification, in which—

10 A represents the concave central portion or body of the bracelet, and b c the border.

The central concave portion, A, may be plain, as shown, or it may be ornamented, as the taste may suggest. The portion b of the border is convex and c is concave, and both are finely creased or corrugated.

The bracelet may be spun or struck up and

formed from a single piece of metal, and the central portion may be colored so as to produce a fine effect.

20

What I claim as my invention is—

The design for a bracelet, consisting of the central portion or body, A, which is concave, and a border the outer portion of which is convex and the inner portion concave, substantially as described, and shown in the accompanying illustration.

25

In testimony that I claim the foregoing I hereto subscribe my name in presence of two witnesses.

JOHN H. SHOEMAKER.

Witnesses:

OLIVER DRAKE,
CHARLES H. PELL.
